Patented Apr. 11, 1922.

UNITED STATES PATENT OFFICE.

ELVIN B. McCAIN, OF HERSHY, NEBRASKA.

BEET TOPPER.

1,412,696.

Specification of Letters Patent. Patented Apr. 11, 1922.

Application filed November 4, 1920. Serial No. 421,720.

To all whom it may concern:

Be it known that I, ELVIN B. McCAIN, a citizen of the United States, residing at Hershey, in the county of Lincoln and State 5 of Nebraska, have invented certain new and useful Improvements in Beet Toppers, of which the following is a specification.

This invention has for its object the provision of a simple, inexpensive and efficient 10 device for splitting and cutting the tops of beets prior to the lifting of the beets from the ground and seeks to provide such a device which may be easily adjusted to permit the beets to be cut at a desired point 15 below their extreme upper ends and also to provide such a device which will be yieldably mounted so that it may automatically accommodate itself to the heights of different beets above the ground surface.

20 The invention is illustrated in the accompanying drawing, in which—

Figure 1 is a perspective view of a beet topper constructed in accordance with my invention;

25 Fig. 2 is a horizontal section on the line 2—2 of Fig. 1.

In carrying out my invention, I employ a blade 1 which is adapted to run longitudinally of a row of plants and has its front 30 portion upturned, as shown at 2, whereby it will ride over the tops of the beets in the manner of a sleigh runner and will engage the beet tops gradually and thereby avoid such excessive laceration of the beets 35 as would destroy their value. A standard 3 is formed integral with or intimately connected to the longitudinally disposed knife runner 1 intermediate the ends thereof and this standard is adapted to be secured to a 40 cultivator, a beet harvester, or any other convenient or preferred machine. The standard is mounted in a bracket 4 and is movable freely through the same but is prevented from dropping out of the bracket 45 by a pin or other stop 5 inserted transversely through the standard above the lower arm of the bracket, as clearly shown in Fig. 1. The bracket may conveniently be a length of bar iron having its ends bent 50 at right angles to its main portion and provided with angular openings therethrough to receive the standard and prevent relative rotary movement thereof while accommodating the vertical movement of the 55 same. A spring 6 is coiled around the

standard between the upper arm of the same and the stop 5 so as to yieldably hold the blade 1 to its work. The blade will thus be permitted to ride over stones or other unyielding obstacles while it will be held to the beets and will split the tops of the same as is obvious. The standard is provided with a plurality of openings 7 through any one of which the pin 5 may be inserted and obviously a plurality of 60 springs 6 may be provided and used interchangeably so that, in any particular instance, the strength of the apparatus will be proportioned to the size of the beets or other circumstances which determine the 65 needed strength of the working members. The forward vertical midportion of the bracket 4 is provided with a plurality of openings through which fastening bolts 8 are inserted, the said bolts passing through 70 and above and below a beam 9 to secure the device to the beam when nuts 10 on the ends of the bolt are turned home against a clamping plate 11 in an obvious manner.

Upon the sides of the runner blade 1, I 80 provide gage bars 12 which are upturned at their front ends to follow the longitudinal contour of the blade and these gage bars bear upon the tops of the beets and thereby regulate the depth to which they are split 85 by the blade. To adjust the said gage bars as may be needed in any particular instance, I provide a plurality of transverse openings 13 through the blade and the gage bars are secured in position by bolts 14 inserted 90 through the bars and the proper openings, as shown and as will be readily understood. The rear end of the runner blade is enlarged vertically, as shown at 15, and this vertical enlargement may be provided with openings 95 16 to permit the attachment of braces or stop chains or cables which will limit the downward movement of the rear end of the runner relative to the cultivator or other machine to which it is attached so that the 100 rear end of the blade cannot dig into the ground and mash or gouge the beets. The lower edge of this vertical enlargement is cut-away or arched, as indicated at 17, and the ends of this arched portion are bridged 105 by a horizontally disposed blade 18 which is formed integral with or rigidly attached to the end of the runner. This blade is preferably triangular in outline with its side edges diverging rearwardly and its side 110

edges are the cutting edges. It is thought to be obvious that this horizontal blade will follow immediately behind the runner blade and will remove the tops of the beets at both sides of the split produced therein by the forward blade.

It will be readily noted that I have provided an exceedingly simple and inexpensive device which may be readily drawn over the ground and will readily split and remove the beet tops so that it will not be necessary to perform that operation after the beets have been harvested and the progress of the beets through the harvesting machine will be, therefore, expedited. The device is very light and may be readily coupled to any convenient or preferred vehicle.

Having thus described the invention, what is claimed as new is:

1. A beet topper comprising a supporting bracket having upper and lower rearwardly extending arms, a standard mounted in said arms for free vertical movement and restrained against horizontal movement, a

blade carried by the lower end of said standard, a stop on said standard between the arms of the bracket, and a spring coiled around the standard between said stop and the upper arm of the bracket. 25

2. A beet topper comprising a vertically disposed blade adapted to run upon the ground, and a gage bar extending longitudinally of said blade close against the side of the same and following the contour thereof whereby the under side of the gage 35 bar is parallel with the cutting edge of the blade throughout its length.

3. A beet topper comprising a vertically disposed blade adapted to run upon the ground, and stop bars extending longitudinally of said blade close against the sides of the same and vertically adjustable thereon, said stop bars being approximately coterminous with the blade and having their under sides parallel with the cutting edge 45 of the blade throughout their length.

In testimony whereof I affix my signature.

ELVIN B. McCAIN. [L.S.]
